UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

EXHAUST-BOX.

1,286,147.

Specification of Letters Patent. Patented Nov. 26, 1918.

Application filed September 3, 1918. Serial No. 252,372.

To all whom it may concern:

Be it known that I, ALBERT R. THOMPSON, a citizen of the United States, residing at San Jose, in the county of Santa Clara and State of California, have invented certain new and useful Improvements in Exhaust-Boxes, of which the following is a specification.

My invention relates to that class of machines used in the canning art for treating fruit, vegetables, meats, fish and other comestibles, in which the filled cans are carried through a box and subjected therein to a medium for heating, cooling, sterilizing or other effects.

These machines are principally termed in the art, exhaust-boxes, cookers, coolers, sterilizers, etc., and while my invention is applicable to any of them, without regard to its special purpose, it is particularly adapted for that form commonly known as exhaust-boxes, in which the "first cook" is applied, prior to the permanent sealing of the cans.

For the sake of simplicity, I shall, therefore, describe my invention in terms of exhaust-boxes, though it must be understood that I do not limit myself thereto, because said invention is applicable to any machine, irrespective of its name or purpose, through which the cans are carried for the purpose of treating their contents by the employment of any given treating medium.

The object of my invention is to provide a machine of the described character in which the carrier for advancing the cans therethrough is of such a nature as to provide a maximum length of can path consistent with a variety of shapes and dimensions of the box, thus leading to economy in and availability of floor-space.

A further object of the invention, involved in the novel character of the carrier, is the opportunity its arrangement affords for adapting it for the accurate advance of the cans without any danger of catching or interference in passing from one component of the carrier to another. Another object is to provide an improved driving means for the carrier, and an improved construction of the can-guide rails, and means for lubricating the carrier spindles.

To these ends my invention consists in the novel machine, which I shall herein

fully describe by reference to the accompanying drawings in which— 55

Figure 1 is a top plan view of the machine partly broken to show the driving of the disks; and the cover of the tank or box being removed.

Fig. 2 is a side elevation of the machine, 60 the wall of the box being broken in part, showing the interior mechanism in section on the line 2—2 of Fig. 1.

Fig. 3 is an end view broken in part.

Fig. 4 is a cross section on the line 4—4 65 of Fig. 1.

1 is a frame carrying a tank or box 2 of suitable construction, having a cover 2'.

Within the box is a conveyer comprising a line of disks 3 horizontally disposed, said line being parallel with the side walls of the box and each disk having peripheral teeth 4, the teeth of one disk meshing directly with the teeth of a succeeding disk in the line, so that said disks are juxtaposed, 70 and adjacent ones rotate in opposite directions. Motion imparted to one disk will cause the disks of the whole line to rotate in unison. The carrier while it may consist essentially of a single line of intermeshing 75 toothed disks, in practice consists of a plurality of parallel lines in any number, according to the predetermined dimensions of the machine and the floor space available.

In the plural arrangement, the disks of 80 one line do not mesh with those of adjacent lines, and in this arrangement the disks of adjacent lines are staggered, thereby effecting a closeness of the lines, resulting in economy in width of the machine. Overlying the disk lines are the spaced can-rails 85 which define the side limits of the can path. These rails have a sinuous or serpentine course, over each line of disks, and are so proportioned with respect to their flexures that they overlie relatively opposite partial areas of adjacent disks of each line, and pass continuously from the end or terminal disk of one line to the initial disk of the adjacent line, so that the can path defined by them is a continuous one to and fro, beginning at the first disk of the first line and ending at the last disk of the last line.

The initial disk of the first line, which is 90 here indicated by 3^a is the entering disk.

and lies partly without and partly within the box or tank 2 projecting through the can inlet 31 thereof; and the end or delivery disk of the last line, indicated by 3^x, in similar manner projects through the delivery opening 32 of the box or tank 2.

Heat is supplied by any suitable medium, in practice by steam supplied by perforated steam pipes entering the box at 6 and thence 10 rising to a cross header 7 from which they branch at 8 on each side and at 9 in the middle and these extend the length of the box.

A carrier of this arrangement of disks in 15 the lines described is especially adapted for the provision of means for preventing any possibility of the catching of the cans in their transfer from one disk to the other. It is a difficult matter to initially arrange and 20 keep the disks in such perfect surface alignment that a succeeding disk will not have its receiving edge a little higher than the delivery edge of the preceding disk, in which case the cans will catch on said edge 25 with disastrous results. If, however, the disks be mounted for angular surface adjustment in the direction of the can travel, the disks may be either accurately leveled or, if desired, the receiving edges of succeeding 30 disks may be very slightly dropped below the delivery edges of preceding disks, so that all danger of the cans catching will be absolutely avoided.

It will now be seen that in the line arrangement of the disks of my carrier, because the cans pass upon, and travel from each disk on opposite sides, this tilting of the disks is possible, whereas if the cans entered upon and left a disk on the same side, 40 as has been the case heretofore in the common form and arrangement of this type of disk carrier where the cans travel back and forth between two lines of staggered disks, such tilting of the disks is impossible, for if 45 a given disk were angularly depressed with relation to its preceding delivery disk, it would be also depressed with relation to its succeeding receiving disk and a step would be formed which would be a fatal rise.

50 The necessity for a tilting relative adjustment of the disks, either to accurately align their surfaces or to provide the step down effect has proven in practice to be of great value, and particular attention is called to 55 the fact that the straight away line arrangement of the carrier herein disclosed not only results in the general advantage of conserving floor-space, by adapting the dimensions of the machine to the available room, but 60 also lends itself to the tilting adjustment of the disks.

I shall now describe a practical means for effecting this adjustment, though it will be understood that I do not confine myself to 65 these specific means.

Each disk has a hub 10, as seen in Fig. 4, by which it is mounted for rotation upon a fixed spindle 11. The spindle at its lower end is fixed by a set screw 12 in the upper end of a bearing 13 the foot of which is pivotally mounted on a bolt 14, set in the vertical flange of a horizontal longitudinal angle frame member 15. The mounting is such that the bearing 13 and spindle 11, together with the disk they carry, may be 70 tilted in the direction of the disk line which is the direction of the can travel.

In order to effect and control this tilting movement, the foot of the bearing 13 is provided with lugs 16, (Figs. 2 and 3) on opposite sides, projecting at right angles to the center of rocking movement. In each of these lugs is fitted an adjusting screw 17, which bears upon the horizontal flange of the angle frame member 15. By manipulating 85 these screws 17, the disk may be tilted as desired and held in the position to which it is adjusted.

In order to conveniently operate these screws 17, I provide holes 18 in the disk, 90 as seen in Fig. 1, through which a tool may be inserted to reach them.

The upper end of the disk spindle 11 is fixed by a set screw 19, as seen in Fig. 4, in the tubular top of a fixed bracket 20.

95 Into the top of this bracket is set a screw cap 21, between which and the top of the spindle is left a small space 22 for the reception of the spindle lubricant.

These brackets 20 serve a second useful 100 constructive purpose. As shown in Fig. 1, they are provided with wings 23, to which the can-rails 5, which are conveniently made in relatively short sections, are secured.

The power to revolve the disks enters 105 from the shaft 24, controlled by a clutch-lever 25. The shaft 24 extends transversely of the box, and is provided with bevel pinions 26, here shown as three in number.

In the frame are suitably mounted three 110 vertical shafts 27, the lower ends of which carry bevel gears 28 with which the bevel pinions 26 respectively engage. The upper ends of the shafts 27 carry pinions 29.

The particular disks 3 in all the lines, 115 which lie above the power shaft 24, are provided with underlying gears 30 one for each disk. With the gears 30 of the disks of two adjacent lines, the pinions 29 of the shafts 27 engage, as is shown in the broken portion 120 of Fig. 1. Thus a single power shaft transversely of the machine drives all the lines.

The operation of the machine is as follows:—Cans supplied to the entering disk 3^x, and resting thereon are carried between 125 the rails 5, into the box and pass to the next disk of the first line and upon its partial area they are carried to the opposite partial area of the following disk and so on to the end of the line, where they pass to the initial 130

disk of the second line, and back upon said second line in the sinuous course defined by the rails 5, to the initial disk of the third line, upon which they pass forward again, 5 and so on to and fro, to the end or delivery disk 3^x of the last line by which they are carried out of the box.

It will now be seen that within a given area, of whatever shape, as to relative length 10 or width, the maximum length of can path is obtained, thereby suiting the machine to the character and dimensions of the floor space available. The machine may therefore be a long one, or a wide one, to accommodate 15 the conditions of installation. It will also be seen that the disks may be tilted in the direction of the line, so that their surface alinement is provided for or if found best a step down may be had from one disk to 20 the next, so that the cans will not catch on any projecting shoulder.

I claim:—

1. In an apparatus of the described character the combination with a box, of a carrier therein comprising juxtaposed, horizontal disks for supporting and advancing the cans, said disks being arranged in a line parallel with the sides of the box; means for effecting the rotation of adjacent disks in 25 said line in relatively opposite directions; and means for directing the cans to and upon relatively opposite areas of adjacent disks continuously throughout the length of said line.
2. In an apparatus of the described character, the combination with a box, of a carrier therein comprising a plurality of parallel adjacent lines of juxtaposed, horizontal disks for supporting and advancing the 30 cans, said lines being parallel with the sides of the box; means for effecting the rotation of adjacent disks in each line and the terminal disks of adjacent lines in relatively opposite directions; and means for directing 35 the cans to and upon relatively opposite areas of adjacent disks of each line and to and upon the terminal disks of adjacent lines continuously throughout the combined length of said plural lines.
3. In an apparatus of the described character, the combination with a box, of a carrier therein comprising juxtaposed, horizontal disks for supporting and advancing the cans, said disks being arranged in a line 40 parallel with the sides of the box, and each disk being tilttable in the direction of the line; means for rotating adjacent disks in said line in relatively opposite directions; and means for continuously directing the 45 cans from one side of one disk to the opposite side of a succeeding disk, throughout the length of the line.
4. In an apparatus of the described character, the combination with a box, of a carrier therein comprising a plurality of par-

allel, adjacent lines of juxtaposed, horizontal disks for supporting and advancing the cans, said lines being parallel with the sides of the box, and each disk being tilttable in the direction of the line; means for effecting 70 the rotation of adjacent disks in each line and the terminal disks of adjacent lines in relatively opposite directions; and means for continuously directing the cans from one side of one disk to the opposite side of the 75 succeeding disk in each line and from the terminal disk of one line to the initial disk of the succeeding line throughout the plurality of lines.

5. In an apparatus of the described character, the combination with a box, of a carrier therein comprising juxtaposed, horizontal disks for supporting and advancing the cans, said disks being arranged in a line parallel with the sides of the box; means 80 for rotating adjacent disks in the line in relatively opposite directions; means for tilting each disk in the direction of the line and locking it in the position adjusted; and means for directing the cans to and upon 85 relatively opposite areas of adjacent disks continuously throughout the length of said line.

6. In an apparatus of the described character, the combination with a box, of a carrier therein comprising juxtaposed, horizontal disks for supporting and advancing the cans, said disks being arranged in a line parallel with the sides of the box; means for rotating adjacent disks in the line in 90 relatively opposite directions; means for directing the cans to and upon relatively opposite areas of adjacent disks continuously throughout the length of said line; and means for tilting each disk in the direction of the line, comprising a spindle upon 95 which the disk rotates, a rocking bearing carrying said spindle, and adjusting screws for rocking and controlling said bearing.

7. In an apparatus of the described character, the combination with a box, of a carrier therein comprising juxtaposed, horizontal disks for supporting and advancing the can; means for rotating adjacent disks in 100 relatively opposite directions; fixed brackets overlying the axis of rotation of said disks; and sections of guide rails secured to said brackets for directing the cans to and upon relatively opposite areas of the adjacent disks.

8. In an apparatus of the described character, the combination with a box, of a carrier therein comprising juxtaposed, horizontal disks for supporting and advancing the cans; means for rotating adjacent disks in 110 relatively opposite directions; fixed tubular headed brackets overlying the axis of rotation of the disks; spindles upon which the disks rotate, said spindles being fitted in the tubular brackets; screw caps in the tubular 115

120

125

130

- heads of the brackets for confining a lubricant for the spindles; and can guide-rails secured to the brackets and overlying the relatively opposite areas of adjacent disks.
- 5 9. In an apparatus of the described character, the combination with a box, of a carrier therein comprising a plurality of parallel, adjacent lines of juxtaposed, horizontal, peripherally-toothed disks, the disks of
- 10 each line successively intermeshing, for supporting and advancing the cans, said lines being parallel with the sides of the box; a power shaft directed transversely to said lines; vertical shafts driven by the power shaft; and power transmitting devices be-
- 15 tween each of said vertical shafts and adjacent disks in adjacent lines; and means for directing the cans to and upon relatively opposite areas of the adjacent disks of each line and from the terminal disk of one line 20 to the initial disk of the succeeding line throughout the plurality of lines.
- In testimony whereof I have signed my name to this specification in the presence of two subscribing witnesses.

ALBERT R. THOMPSON.
